UNITED STATES PATENT OFFICE

123,630

DESIGN FOR A GAME BOARD OR SIMILAR ARTICLE

Hy Shevey, New York, N. Y.

Application July 16, 1940, Serial No. 93,675

Term of patent 7 years

To all whom it may concern:

Be it known that I, Hy Shevey, a citizen of United States, residing in New York, in the county of New York and State of New York, have invented a new, original, and ornamental Design for a Game Board or Similar Article, of which the following is a specification, reference being had to the accompanying drawing forming part hereof, wherein—

I claim:

The ornamental design for a game board or similar article, substantially as shown.

HY SHEVEY.
